UNITED STATES PATENT OFFICE

2,638,027

WIND INSTRUMENT

Gaston M. Strobino, Chicago, Ill.

Application July 17, 1947, Serial No. 761,544

3 Claims. (Cl. 84—380)

1

This invention relates to a musical instrument and particularly to a wind instrument. It has for one object to provide a simple wind instrument which can be played readily and with which control is accomplished by the hands which are applied to openings in the instrument.

Another object is to provide a wind instrument without reeds or other comparable members.

Other objects will appear from time to time throughout the specification and claims.

This invention is illustrated more or less diagrammatically in the accompanying drawings, wherein:

Figure 1 is a top plan view of one form of the device;

Figure 2 is a section taken at line 2—2 of Figure 1;

Figure 3 is a top plan view of a modified form of the device;

Figure 4 is a plan view of the device of Figure 3, the view being taken at an angle of 90° from that of Figure 3;

Figure 5 is a section taken at line 5—5 of Figure 4;

Figure 6 is an end elevation of the device shown in Figures 3, 4 and 5.

Like parts are indicated by like characters throughout the specification and the drawings.

In general the device includes a housing or sound chamber with an opening which can be more or less closed by the hands or fingers of the player. It includes also a windpipe through which a blast of air is directed, and it includes an opening across and into which the blast of air is directed. A throat or ledge extends across the path of entering air, which has a groove cut into it, the front end of said groove being cut back to form an outlet for air blown into the windpipe.

In the form of Figures 1 and 2 the wind chamber 1 may be made of a plurality of parts joined together by screws 2, or otherwise. As shown particularly in Figure 2, this chamber is provided with an opening or slot 3 in the bottom. It is also provided with a smaller opening 4, and it is shaped to provide an elevation or throat defining member 5 adjacent the member 4.

6 is a wind tube or pipe which may be flared, as at 7, to receive the lips of a player. The blast of air for playing is directed through the pipe 6. The pipe is secured to the chamber 2 by screws 8, or otherwise. As shown, the passage 9 within the pipe 6 is directed toward the opening 4. The lower portion of the passage 9 is, however, below the

2

upper edge of the throat or ledge member 5, as shown particularly in Figure 2. Adjacent the ledge member 5 is formed a depression 10 which is below the bottom or lower portion of the passage 9. The front edge 15 of this depression is cut back, forming a D-shaped hole at the front of the passage 9.

If desired, a rubber or other elastic member 11 may be secured across a portion of the opening 4.

10 As shown, it is held in place by members 12 which are themselves removably held in place by thumb screws 13.

In the modified form of Figures 3 to 6, inclusive, the chamber is elongated and thus a hollow housing 14 defines the chamber. As shown in Figure 3 this housing is provided with two slots 13 and 15. It is provided with openings 16 and 17 in its ends. If desired, the opening 17 may receive a pitch controlling shutter member. As shown, 15 this includes a housing 18 and a reduced portion 19 which fits into the opening 17. Segments 20, 20 are fixed to a collar 21 which carries handles 22. Segments 23, 23 are fixed within the housing 18. Thus by movement of the collar 21 and the 25 segments 20, the openings through the housing 18 may be closed or adjusted to vary the pitch of the instrument.

A tubular member 24, preferably flared as at 25, is fixed in relation to the opening 26 formed in the housing 14. The opening 26 is formed in the wall of the housing 14. It is elongated, as shown in Figure 4, and is generally in line with the member 24. A throat or ledge defining member 27 is positioned adjacent the opening 26. 30 The member 27 directs air from the tube 24 upwardly across the opening 26, as shown by dotted lines in Figure 5. As shown particularly in Figure 5, the bottom of the passage 28 formed within the member 24 is below the upper portion of 35 the ledge 27. It is above a depression or groove 29 formed adjacent the ledge 27.

Although I have shown an operative form of my invention, it will be recognized that many changes in the form, shape and arrangement of 40 parts can be made without departing from the spirit of the invention, and my showing is therefore to be taken as, in a sense, diagrammatic.

The use and operation of this invention are as follows:

45 In the various forms shown the playing of the device is substantially the same. The device is held in one or two hands, the lips are applied to the windpipe and a blast of air is blown through this pipe toward the chamber in the housing in any of the various forms. The hands or fingers

of the operator are applied to the opening or openings in the chamber. The only opening which is not directly controlled by the hands or fingers of the operator is that across which the blast of air is directed from the windpipe. As the air enters through the windpipe it strikes the throat or ledge member and is deflected upwardly and outwardly from the chamber. Thus the part 5 in Figures 1 and 2, the part 27 in Figures 3, 4, 5 and 6 are baffles for the incoming air. The passage of the air is illustrated by the arrows in Figure 5.

The air entering through the pipe 24 strikes the groove 29 in the ledge 27 and is deflected through the hole formed by cutting back the front end of the groove, upwardly across the opening 26, thus generating its fundamental note. It thus draws air into the chamber formed by the housing 14, and this air enters through the openings 13, 15, 16 and 17. The variation of this incoming air changes the fundamental note to any note of the chromatic scale.

A corresponding air movement occurs in the other forms of the device, and they need not be redescribed in each case, and the air from the windpipe is blown against a ledge adjacent an opening formed by the grooves 18 and 20 and is deflected upwardly and outwardly across and through the opening. As this movement occurs, some suction is set up and air is drawn into the chamber through the other opening or openings provided in the housing which defines the chamber. Control of the musical notes is provided by controlling and varying with the hand the size of the openings through which air enters the housing to enter the chamber.

In all the forms of the device, the blast of air which comes through the windpipe and strikes across and upwardly with respect to the opening toward which it is directed draws air out of the body of the instrument and the sound is produced at this point. In all of the forms of the device adjacent the inner or discharge end of the windpipe or tube there are both a groove and a notch. The air in each case passes across the opening toward which it is directed. Thus in the form of Figures 1 and 2 the air passes across the opening 4 but is not blown into it. Similarly, in the forms of Figures 3 to 6, inclusive, the air passes upwardly and across the opening 26.

I claim:

1. In combination, in a musical instrument, means defining a resonance chamber, said resonance chamber shaped to provide a plurality of openings spaced apart, an aperture formed in said means and positioned between said openings, a deflecting surface forming member positioned adjacent said aperture, a groove positioned along the lower edge of said surface forming member, and a windpipe connected to said means and directed to discharge air against said deflecting surface forming member and thereafter across

said opening, whereby air blown through said windpipe is discharged against said deflecting surface and is deflected above and across said aperture and establishes an air current across said aperture which is effective to draw air from said resonance chamber and to create a musical note.

2. In combination, in a musical instrument, means defining a resonance chamber, said resonance chamber shaped to provide a plurality of openings spaced apart, an elliptically shaped aperture formed in said means and positioned between said openings, a deflecting surface forming member positioned adjacent said elliptical aperture, a groove positioned along the lower edge of said surface forming member, and a windpipe connected to said means and directed to discharge air against said deflecting surface forming member and thereafter across said opening, whereby air blown through said windpipe is discharged against said deflecting surface and is deflected above and across said elliptical aperture and establishes an air current across said aperture which is effective to draw air from said resonance chamber and to create a musical note.

3. In combination, in a musical instrument, means defining a resonance chamber, said resonance chamber shaped to provide a plurality of elongated slots spaced apart adjacent the top of said means, an elliptically shaped aperture formed in said means and positioned between said slots, a deflecting surface forming member positioned adjacent said elliptical aperture, a groove positioned along the lower edge of said surface forming member, and a windpipe connected to said means and directed to discharge air against said deflecting surface forming member and thereafter across said slot, whereby air blown through said windpipe is discharged against said deflecting surface and is deflected above and across said elliptical aperture and establishes an air current across said aperture which is effective to draw air from said resonance chamber and to create a musical note.

45 GASTON M. STROBINO.
